UNITED STATES PATENT OFFICE.

WILLIAM P. NELSON, OF ST. LOUIS, MISSOURI.

SHAVING-PAPER HOLDER.

SPECIFICATION forming part of Letters Patent No. 758,096, dated April 26, 1904.

Application filed July 15, 1903. Serial No. 165,687. (No model.)

To all whom it may concern:

Be it known that I, WILLIAM P. NELSON, a citizen of the United States, residing in the city of St. Louis, in the State of Missouri, have 5 invented certain new and useful Improvements in Shaving-Paper Holders, of which the following is a full, clear, and exact description, reference being had to the accompanying drawings, forming part of this specification.

10 My invention relates to a shaving-paper holder; and it consists in features of novelty hereinafter fully described, and pointed out in the claims.

15 The object of my invention is to provide a simple and neat-appearing holder for shaving-paper.

Figure I is a perspective view of my improved shaving-paper holder. Fig. II is a vertical sectional view taken on the line II II, 20 Fig. I. Fig. III is a view in perspective of a portion of the holder.

Referring to the numerals of the accompanying drawings, 1 is the base, which is provided with a standard 2, in which is seated a 25 vertically-arranged pin 3, provided adjacent its top with a bearing-disk 4, and its upper end terminates in an enlarged pointed head 5. Rotatably arranged upon the bearing-disk 4 immediately below the head 5 is the paper-carrying member, comprising the disk 6 and a 30 series of radiating arms 7, the outer ends of which are turned downwardly, as indicated by 8. A rectangular bent guard 9 is secured to the pin 3 at a point below the disk 4 and 35 extends thence outwardly to a point beyond the ends of the arms 7, from thence upwardly into a plane slightly above said arms 7, and from thence inwardly toward the center of the device. This guard serves the purpose of 40 holding the edge of the paper down should the device be in use where the wind or a draft of air is liable to strike the paper.

In the use of my improved device the edge of the paper is passed underneath the portion of the guard 9 that lies in a plane above the 45 paper-carrying member, and the center of the sheet of paper is forced downwardly past the head 5, this position being shown by dotted lines, Fig. II.

A device of my improved construction is 50 very handy, very conveniently holds the paper when in use, and may be so constructed and finished as to present a very ornamental and neat appearance.

I claim as my invention—

1. In a device of the class described, a base, a standard mounted thereon, a guard-pin positioned in the upper end of the standard, and a paper-receiving member rotatably carried by said guard-pin, substantially as specified. 60

2. In a device of the class described, a standard, a pin fixed in the upper end of said standard, a paper-carrying member rotatably positioned upon said pin, a guard carried by said pin which guard passes around and above the 65 outer edge of the paper-carrying member, substantially as specified.

3. In a device of the class described, the combination of a standard, a rotatable disk mounted on the standard, arms radiating from the 70 disk, and means for holding the paper on the disk, substantially as set forth.

4. In a device of the class described, the combination of a standard, a rotatable disk mounted on the standard, arms radiating from the 75 disk and having downwardly-turned outward ends, and means for holding the paper on the disk, substantially as set forth.

WILLIAM P. NELSON.

In presence of—

NELLIE V. ALEXANDER,
BLANCHE HOGAN.
